UNITED STATES PATENT OFFICE.

ABRAHAM SACKS, OF BROOKLYN, NEW YORK.

TASSEL.

Application filed December 3, 1921. Serial No. 519,644.

To all whom it may concern:

Be it known that I, ABRAHAM SACKS, a citizen of the United States, and a resident of the city of New York, borough of Brooklyn, in the county of Kings and State of New York, have invented a new and Improved Tassel, of which the following is a full, clear, and exact description.

The present invention relates to new and useful improvements in the manufacture of tassels and it pertains more particularly to tassels formed from silk strands and used for ornaments for personal wear.

It is one of the objects of the present invention to provide a new and improved form of tassel head.

It is a further object of the invention to provide new and improved means for finishing a tassel head.

It is a still further object of the invention to provide a finishing means for tassel heads which finishing means may be removed when desired for the purpose of repairing the tassel.

With the above and other objects in view, reference is had to the accompanying drawings in which:

Figure 1 is a sectional view of a tassel constructed in accordance with the present invention, and

Fig. 2 is a view in elevation of the finishing means employed.

In the drawings, a mold 6 is provided with an enlarged head 20 and an elongated neck portion 21. A longitudinal passage 11 extends entirely through the mold and a cord 15 is adapted to be passed through the mold and knotted as indicated by the reference character 16.

The bunch 5 has its upper portion contracted by the cord 10 and the mold 6 is entirely enclosed within the tassel bunch.

After this has been done a coil 25 is passed over the neck portion of the mold 6 and the tassel is compressed by said coil against said neck portion, the lower end of the coil terminating at a point adjacent the enlarged head 20 of the mold.

When it is desired to repair the tassel it is only necessary to remove the coil 25 by sliding the same over the cord 15 at which time the mold 6 together with the cord 15 will be capable of removal from the tassel bunch 5. From the foregoing it will be apparent that the present invention provides a new and novel tassel which may be readily assembled or disassembled without injury to the several parts thereof.

Furthermore in tassels formed in this manner the finish for the mold is not glued thereto as is the common practice but is made bodily removable thereby greatly adding to the life and durability of the tassel.

I claim:

In a tassel, a mold provided with a longitudinal passage, an attaching cord passing through said longitudinal passage and secured therein, a tassel bunch carried by the mold and having its upper end contracted around the cord passed through the tassel mold and a finish in the form of a coiled resilient member adapted to be passed over the mold and into engagement with the tassel bunch to cause the same to frictionally engage the tassel mold, said finish being bodily removable from the mold.

ABRAHAM SACKS.
